PAPER PASTING AND CUTTING DEVICE

Charles A. Golder, Bethel, Conn.

Application June 23, 1932, Serial No. 618,963

10 Claims. (Cl. 91—14)

This invention relates to improvements in devices for applying paste to and cutting paper. While described in relation to the application of paste to wall paper and the cutting, for example, of the molding edge from such paper, the invention is not so limited in its application and has utility in other associations and for other purposes.

An object of the invention is the provision of a device for applying paste to and cutting paper, which has a minimum number of parts and is thereby relatively simple and inexpensive in construction. A further object is the provision of a device of the character described which is durable in use, efficient in operation, and which well fulfills the ends for which it is designed. A further object is the provision of a device of the character described having special utility in the treatment of wall paper prior to hanging, the use of which eliminates the hitherto manual and separate steps of applying the paste or adhesive to the paper and of cutting the molding edge from the paper so that the paper strips may be suitably matched and hung, and/or of cutting the conventional widths of paper into special widths. A further object is the provision of a device of the last above-named character which is portable whereby it may be expeditiously carried to and from the location of use.

Other objects will be in part obvious from the annexed drawing and in part hereinafter indicated from the following analysis of the invention, in which reference is made to the accompanying drawing illustrating an embodiment of my idea.

In the drawing—

Fig. 1 is a perspective view of my device as aforesaid;

Fig. 2 is a transverse section through the device shown in Fig. 1;

Fig. 3 is an enlarged sectional view, certain parts being broken away; and

Fig. 4 is a sectional detail along lines 4—4 of Fig. 1.

Referring now to the drawing, reference character 10 indicates generally a supporting frame which may comprise a horizontal base 11 and side pieces 12, 13, respectively. Journaled between the side pieces, and preferably between the lower portions thereof, is a cylindrical roll 14 hereinafter referred to as the paste applying roll. Said roll 14 is made up of tubular stock, its ends being closed by the end plates 14a in which are fixed the shafts 14b which extend through aligned casting bosses 14c formed in the side

plates 12, 13, as illustrated. Preferably the shafts 14b are mounted in ball bearings 15 arranged in said bosses, whereby the roll 14 is permitted relatively free rotation about a fixed axis. The peripheral surface of the roll 14, as well as the adjacent peripheral surfaces of the end plates 14a, are cross-knurled, the purpose of which will be more fully described hereinafter.

The side pieces 12, 13 of the frame 10 are preferably of substantially U-shape construction, the inner surfaces of each of the legs thereof being machined to form ways 16, in which slides 17, 18, one for each of the side pieces 12, 13, are mounted for movement relative to the side frames.

The said slides 17, 18 provide a journal mounting for a cylinder roll 20, hereinafter referred to as the pressure roll. The said roll 20 is preferably of tubular construction, its ends being closed by end plates 20a from which extend the stub shafts 20b mounted in ball bearings which in turn are mounted in the slides 17, 18 as illustrated. The slides 17, 18 are connected by a cross head 22 and secured thereto as by bolts 23. Thus, as movement is imparted to the head 22, the slides 17, 18, and pressure roll 20 move therewith.

One form of actuating the head 22 and slides 17, 18 is illustrated in the drawing and consists, in conjunction with the top cross piece 25 extending between the side pieces 12, 13 and secured thereto as by bolts 26, of a lever 27 fulcrumed in a yoke 28 fixed on the top frame member 25. The lever arm extends beyond the fulcrum point and is flexibly joined to rod 30 which extends through a suitable aperture in the top frame element 25 and is fixed to the cross head 22 as by bolts 3. Intermediate the yoke 28 and one of the side pieces and in the direction of the longer arm of the lever 27, I arrange a fixed strap 32 having an overhanging end under which the lever 27 may be passed.

It will be seen that the lever may be manipulated about its fulcrum point in such manner as to raise and lower the cross head 22 and the associated slides 17, 18. The pressure roll 20 journaled in the slides 17, 18 is similarly actuated. This movement permits the roll 20 to be raised from its normal position in which by gravity it contacts with the peripheral surface of the paste applying roll 14.

The side blocks 17, 18 also carry cutting means which operate in conjunction with the pressure roll 20 and are operative, for example, to cut the edge molding from a web of wall paper. The cutting means, in the form illustrated, may comprise spaced cutter discs 35 detachably secured

to a rod 36 which is journaled for rotation in the slides 17, 18 and extends therebetween. The rod is preferably mounted in box or self-locating ball bearings 37 arranged in substantially rectangular apertures 38 in the slides 17, 18. The cutters 35 are arranged to bear against the pressure roll 20 to cut a web passing between the knives and said roll. Preferably, the knives are spring-pressed against the roll 14 and this spring pressure may be varied. To effect such a relation, the slides 17, 18 are each bored as at 40 for the reception of helical springs 41, which are arranged to bear against the box of bearings 37 as illustrated. Each of said springs is compressed 15 between the bearing case by a screw 42 threaded into the upper end of the bores 40, and the screws may be turned manually as by a key 43 which extends through the cross part 25 to vary the compression of the spring 41 and thus to vary 20 the pressure contact between the cutter disc 35 and the pressure roll 20.

According to my invention, I provide two sets of cutter discs, of which the discs 35 mounted on rod 36 are intended to cut from paper such as 25 wall paper the molding edge whereby the paper may be suitably matched for hanging. The other set of cutters 35a, which are also preferably of disc type, is mounted on a second rod 36a extending between the slides 17, 18 and similarly 30 mounted in box bearings 37a. The latter described cutter means are similarly cooperatively related with the pressure roll 20 and are resiliently urged thereagainst by springs 41a arranged to be adjusted in the manner of adjustment of springs 41.

The cutter discs are each provided with a hub through which may extend a set screw 45 or the like operative to hold the discs in a predetermined position on the rod. Thus the cutters 35, 35a 40 may be moved axially of the rods 36, 36a to bear against the pressure roll 20 or may be moved to clear the ends of said pressure roll.

When either series of cutters is positioned to bear against the pressure roll 20, it may be desirable 45 to move the cutters from such engagement without disturbing their lengthwise position in relation to their carrying rods, as for example when positioning a new web to be cut in similar widths as a preceding web. To effect such disengagement, I provide means to move the rods bodily away from the roll 20. Such means is 50 illustrated in Fig. 3 and may comprise lever arms 46, 46a cooperating with the rods 36, 36a, respectively, and pivoted intermediate their ends to the slide 17. One such lever arm and its relation to rod 36 will be described. Preferably the lower end as illustrated of lever 46 is provided with an operating handle 47, the other end forming a cam surface 48 which bears against a projecting end 55 of the cutter carrying rod 36. As the handle 47 is rotated in a clockwise direction, Fig. 3, it will be seen that its camming end passes under the projecting end of the rod 46 to raise the same. The raising movement is sufficient to cause clearance 60 between the cutting edge of the cutter 35 positioned adjacent that end of rod 36 and the pressure roll. Similarly, the lever 46a cooperates with the projecting end of the rod 36a whereby such rod may be similarly raised to actuate its cutter or cutters out of engagement with the pressure roll. Normally, the cutters 35a are used 65 only in cutting special widths of the paper and their usual position is such as to clear the ends of the pressure roll 20.

In some instances, it is advantageous to cut

only one edge molding of the paper, while under other conditions both edges are to be cut therefrom. To effect the former condition, the rod 36 may be raised at one end only, by actuating lever 46, to carry the cutter adjacent that end of the rod out of cutting cooperation with the roll 20. To meet the latter condition, that is, when the cutters at both ends of the rod are operative to cut both edges from the paper, the handle 46, illustrated in its full line position, Fig. 3, is not 10 disturbed.

In other instances, it is advisable to move the cutters at both ends of the rod from engagement with the roller 20 and, accordingly, I provide a similar rod actuating means on the slide 18, by 15 the operation of which the rod 36 may be raised bodily, thus to carry the cutters 35 away from the roll 20. When cutters 35a are moved axially into cutting engagement with the roll, levers 46a arranged on the slides 17, 18 may effect a similar 20 end or body actuation of the rod 36a.

Beneath the paste roll 14, I arrange a paste reservoir which may comprise a pan 50 as illustrated. The said pan is provided with studs or projections 51 which engage in slots formed in 25 straps 52 extending from the base 11 of the frame, or from the side brackets 53 auxiliary to the side pieces 12, 13 of the frame. It will be understood that the pasting roll 14 dips into the adhesive carried by the pan 50 and that the cross-knurl 30 on the peripheral surface thereof maintains a sufficient amount of the paste on such surface so that it may apply the paste to a paper web coming in contact therewith.

A paper guide 55 is associated with the device 35 as aforesaid and may take the form of an inclined table as illustrated in Figs. 1 and 4. The said table has its front end supported on any desired surface such as a work bench, and its other end may bear on a cross rod 56 extending 40 between the side frames 12, 13 and forwardly thereof. The paper to be pasted and cut may be laid on the guide after having previously been 45 matched and cut into proper lengths, the height of the rear edge of the table being sufficient to deliver the edge of the paper substantially between the rolls 14, 20.

In order to direct the paper between the rolls, the guide table is formed with a fixed side edge 57 and with a movable side edge 58 which may be 50 adjusted across the width of the table to the width of the paper being treated. The adjustable side piece 58 is held to the table by means of bolt 59 and associated wing nuts 60, the bolts being movable throughout the length of adjusting slots 61 55 formed in the table. A rod 62 extends between the side edges 57, 58 and is slightly raised from the upper surface of the table to permit the web being threaded between the table and the rod.

After cutting of the edge moldings from the 60 paper, it is desirable to separate such molding from the body portion of the web and to effect this I provide molding guides 63, one mounted at each side of the machine. Said guides are preferably of V-shape construction and are mounted 65 from adjusting bolts 64 in the side frames which extend through eyes 65 formed with the guides. Thus the guides may move transversely of the roll 20 to accommodate the different widths of molding edges being cut. To adjust the guides further, the same are partially supported by springs 66 which are carried on studs 67 similarly carried in the side frames 17, 18.

The shafts 14b, 20b which carry respectively 70 the rolls 14 and 20 may extend beyond the plane 75

of the side frames 12, 13 and are provided with operating handles 68, 69 whereby the rolls 14 and 20 may be manually turned.

In use, a web of paper is laid on the table 55 with its surface to be pasted facing downwardly. The paper is pushed forward to extend between the rolls 14 and 20, and by manual turning of the handles 68 or 69, the paper is extended between said rolls. Alternatively, the pressure roll may be raised by manipulation of lever 27 and the paper manually threaded between the rolls. The paper is then brought about the pressure roll 20, the cutter carrying rod 36 (or 36a, or both) being raised by manipulation of their raising handle 46. Upon proper adjustment of the cutter, that is to say, to cut off the required widths of the paper, the handle 46 is released and the knives drop into cutting engagement with the roll 20. The paper passing forwardly between the cutters and the pressure roll may then be grasped and pulled forwardly, causing the rollers 14, 20 to rotate due to the weight of the pressure roll 20 and its mounting assembly. The paste carried on the surface of the roll 14 is applied to the under surface of the paper and the paper is cut by passing under the rollers 35 (or 35a). Where a molding edge has been cut, the cut molding may be laid upon the guides 63, and continued pasting and cutting of the paper causes the cut molding to be diverted sidewardly where it may fall into a receptacle or the like. The pasted and cut web may then be delivered to the workmen engaged in hanging the paper.

Without further analysis the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

45 I claim:

1. In a device of the character described, a paste carrying roll, a vertically movable pressure roll adapted to press a web passing between said rolls against the first roll, thereby applying paste to one surface of the web, means to actuate the pressure roll out of such pressure relation, the pressure roll being movable by gravity into such pressure relation upon release of said means, cutting means bodily movable with said pressure roll, and resilient means urging said cutting means into cooperative cutting relation with said pressure roll.

2. In a device of the character described, a paste carrying roll, a vertically movable pressure roll adapted to press a web passing between said rolls against the first roll thereby applying paste to one surface of the web, means to actuate the pressure roll out of such pressure relation, the pressure roll being movable by gravity into such pressure relation upon release of said means, cutting means bodily movable with said pressure roll, resilient means urging said cutting means into cooperative relation with said pressure roll, and means to vary the effect of said resilient means.

3. In a device of the character described, a paste carrying roll, a vertically movable pressure roll adapted to press a web passing between said rolls against the first roll thereby applying paste to the surface of the web, means to actuate the

pressure roll out of such pressure relation, the pressure roll being movable by gravity into such pressure relation upon release of said means, and cutting means bodily movable with said pressure roll and including spaced cutters normally engaging said pressure roll, and means to actuate said cutters into and out of such engagement.

4. In a device of the character described, a paste carrying roll, a vertically movable pressure roll adapted to press a web passing between said rolls against the first roll, thereby applying paste to one surface of the web, means to actuate the pressure roll out of such pressure relation, the pressure roll being movable by gravity into such pressure relation upon release of said means, and cutting means bodily movable with said pressure roll and including spaced cutters normally engaging said pressure roll, and means to actuate one or all of said cutters out of engagement.

5. In a device of the character described, a support including side pieces, a roll mounted for rotation between said side pieces, a slide operatively mounted in each of said side pieces, a pressure roll journaled in said slides, cutting means carried by said slides and arranged in cutting engagement with said pressure roll, manual means for actuating the slides whereby to bring the pressure roll into and out of pressure relation with the first roll, and means carried by said slides for actuating said cutting means into and out of cutting engagement with said pressure roll.

6. In a device of the character described, a support including side pieces, a roll mounted for rotation between said side pieces, a slide operatively mounted in each of said side pieces, a pressure roll journaled in said slides, a rod extending between said slides and journaled therein, cutting means carried by said rod and normally engaging said pressure roll, and means carried by a slide operative to actuate the rod toward and away from the pressure roll.

7. In a device of the character described, a support including side pieces, a roll mounted for rotation between said side pieces, a slide operatively mounted in each of the side pieces, a pressure roll journaled in said slides, a rod extending between said slides and journaled therein, cutting means carried on said rod and engaging said pressure roll, and means carried by each of said slides and operative to actuate the rod bodily, or one end only thereof, toward and away from the pressure roll.

8. In a device of the character described, a support including side pieces, a roll mounted for rotation between said side pieces, a slide operatively mounted in each of the side pieces, a pressure roll journaled in said slides, rods extending between the slides and journaled therein, cutting means carried by said rods, and means, one for each end of a rod, carried by said slides to actuate the rods toward and away from said pressure roll.

9. In a device of the character described, a supporting frame, a paste reservoir mounted therein, a paste carrying roll journaled in the frame and extending into said reservoir, slides mounted for vertical movement in the frame, a pressure roll journaled in said slides, the slides and the pressure roll being movable downwardly by gravity whereby to establish normally the desired pressure relation between the pressure and paste carrying rolls, cutting means carried by said slides and cooperating with said pressure

roll, and means for actuating the slides upwardly whereby to interrupt said pressure relation.

10. In a device of the character described, a supporting frame, a paste reservoir mounted therein, a paste carrying roll journaled in the frame and extending into said reservoir, slides mounted for vertical movement in the frame, a pressure roll journaled in said slides, the slides and the pressure roll being movable downwardly by gravity whereby to establish normally the de-

sired pressure relation between the pressure and paste carrying rolls, cutting means carried by said slides and cooperating with said pressure roll, means for actuating said cutting means relatively of said slides and pressure roll, and means for actuating the slides and pressure roll upwardly whereby to interrupt said pressure relation.

CHARLES A. GOLDER.
